(74) Attorney, Agent, or Firm—Banner & Witcoff, Ltd.

(57) **CLAIM**

The ornamental design for an electronic computer, as shown and described.

DESCRIPTION

FIG. 1 is a reduced top, front and right side perspective view of an electronic computer showing my new design,

FIG. 2 is a front elevational view thereof,

FIG. 3 is a rear elevational view thereof,

FIG. 4 is a left side elevational view thereof,

FIG. 5 is a right side elevational view thereof,

FIG. 6 is a top plan view thereof,

FIG. 7 is a bottom plan view thereof,

FIG. 8 is a front elevational view showing the article in a closed position thereof,

FIG. 9 is a right side elevational view showing the article in the closed position thereof,

FIG. 10 is a top plan view showing the article in the closed position thereof,

FIG. 11 is a reduced perspective view showing the article with a sub-display being in a closed position thereof; and,

FIG. 12 is a perspective view showing the article in the closed position thereof.

The broken lines are shown in the views for illustrative purposes only and form no part of the claimed design.
